FIG. 3.

UNITED STATES PATENT OFFICE

2,224,405

SKI SLIDE

Charles D. McIntyre, Portland, Oreg.

Application September 21, 1938, Serial No. 231,080

1 Claim. (Cl. 46—17)

The present invention relates to improvements in game apparatus and more particularly to improvements in ski slides.

5 An important object of the invention is to provide a ski slide so constructed that it may be assembled to produce a continuous slideway or a jumping gap, as desired.

10 Another object is to provide a ski slide including structural parts which, upon assembly, are securely connected together but which may be readily intentionally disconnected.

15 A further object of the invention is to provide structural parts which may be assembled into a ski slide in an interesting and educational manner, tending to impart to the erector a basic knowledge of the science of construction engineering.

20 Yet another object is to provide a ski slide including structural parts which may be packed into a relatively small space.

25 A still further object of the invention is to provide an elongate ski slide which may be supported upon an uneven floor, ground or other suitable surface.

30 Other objects and advantages of the invention will become apparent during the course of the following detailed description, taken in connection with the accompanying drawings, forming a part of this specification, and in which drawings:

Figure 1 is a perspective view of the ski slide arranged to provide a jumping gap, and showing a toy ski jumper thereon.

Figure 2 is a perspective view of the ski slide arranged to provide a continuous slideway.

Figure 3 is a perspective view showing in partially disassembled relationship, the arrangement of parts of the ski slide illustrated in Figure 1.

Figure 4 is a vertical sectional fragmentary view taken on the line 4—4 of Figure 1.

40 Figures 5 and 6 are horizontal sectional fragmentary views taken on the lines 5—5 and 6—6, respectively, of Figure 4.

Figure 7 is a plan view of a container for the 45 ski slide and ski jumper and showing a preferred arrangement of the disassembled parts therein.

In the drawings, which show preferred and modified forms of the invention, and wherein similar reference characters denote corresponding parts throughout the several views, A designates a preferred form of the ski slide provided with a jumping gap, B indicates a modified form of ski slide provided with a continuous slideway, C refers to a figure simulating a skier or ski jumper, while D designates a container for packing and

storage of the disassembled parts of the ski slides and jumper.

The ski slide A, shown in Figures 1 and 3, includes an elongate frame 10 formed of wood or metal and comprising forward, intermediate and rear portions 11, 12 and 13, respectively. Each of these portions is independent and adapted to remain upright when resting on a substantially horizontal supporting surface, such as afforded by a floor or table (not shown).

10 The forward portion 11 of the frame may include a pair 14 of relatively short companion uprights; the intermediate portion 12 may comprise pairs 15, 16 and 17 of companion uprights increasing in height toward the rearward pair 15 11 of uprights; and the rear portion 13 may be provided with pairs 18, 19, 20 and 21 of companion uprights further increasing in height toward the rearward pairs 20 and 21, which are preferably of equal height. Secured to the insides of the companion uprights, as by gluing, and at the lower end portions thereof, are blocks 22 providing upper faces 23.

20 Securing the pairs 15, 16 and 17 of companion uprights in longitudinally spaced relation at opposite sides of the frame are stringers 24, resting on the upper faces 23 of the blocks 22 and provided in their outside edges with notches 25 accommodating the uprights. In the same manner, the pairs 18, 19, 20 and 21 are secured in longitudinally spaced relation by stringers 26 provided in their outer edges with notches 27 accommodating the uprights of the rear portion 13.

25 Extending between companion uprights of the intermediate and rear portions 12 and 13 and resting on the stringers 24 and 26 respectively, are cross pieces 28. In their opposite end portions, these cross pieces are provided with notches 29 co-acting with notches 30 in the uprights of the portions 12 and 13 to form halved joints between the cross pieces 28 and companion uprights 15—18, 20 and 21 immediately above the stringers. The notches 30 are so formed that halved joints between the cross pieces 28 and pairs 15, 16, 18 and 20 of uprights are secured by forward movement of the cross pieces over the stringers 24 and 26 relative to the uprights, whereas the halved joints between the remaining cross pieces 28 and pairs 17 and 21 are accomplished by movement of the remaining cross pieces 28 rearwardly of the frame. Secured to the lower surfaces of the cross pieces inwardly of the opposite ends thereof, as by gluing, are ribs 31 abutting the inner edges of the stringers 24 and 26. These ribs 31 secure the stringers 35

against movement inwardly of the sides of the frame and therefore prevent disengagement of the uprights from the notches 27 as long as the cross pieces 28 are in place. As shown in Figures 1 and 4 of the drawings, thumb-tacks 32 may be employed to secure the cross pieces 28 to the stringers 24 and 26 and prevent separation of the halved joint between the cross piece and upright.

Extending between companion uprights of the forward, intermediate and rear portions 11-13 in spaced relation below the upper ends thereof are additional cross pieces or spacers 33, provided, in their opposite end portions with notches 34 co-acting with notches 35 in the uprights to form halved joints between the cross pieces or spacers 33 and the upper end portions of the uprights. The notches 35 of the pairs 14, 15 and 17-19 of uprights incline downwardly and forwardly so that the cross pieces interengaged with these uprights will likewise incline, whereas the notches 35 of the pairs 16, 20 and 21 extend at right angles to the uprights so that the remaining cross pieces form substantially horizontal supports. The arrangement 25 of the notches 35 in the uprights is such that the cross pieces or spacers 33 are moved forwardly of the frame to form halved joints with the pairs 14, 15, 17-19 and 21 but rearwardly of the frame to form halved joints with the pairs 16 and 20 of companion uprights.

Extending rearwardly and upwardly of the rear portion 13 at opposite sides thereof are diagonal braces 36 secured to the uprights as by suitable bolts 37.

At their upper ends the uprights may be provided with ornaments, such as spherical colored glass beads 38, secured to the uprights, as by brads 39.

Secured to the cross pieces or spacers 33, as by thumb tacks 40, is a flexible runway 41, which may be formed of cardboard sheets. In the example shown, three sheets 42, 43 and 44, of identical dimensions are provided. The forward sheet 42 is supported at its intermediate and rear end portions by the cross pieces or spacers 33 carried by the pairs 14 and 15 of companion uprights, in a manner whereby the forward end 45 is adapted to rest upon the upper surface of the floor, table or other support (not shown). The intermediate sheet 43 is supported by the cross pieces or spacers carried by the pairs 16-18 of companion uprights, while the rearward sheet 44 is supported by the cross pieces or spacers 33 carried by the pairs 18-21 of 55 companion uprights with its forward end 46 overlapping the rearward end 47 of the intermediate sheet 43. It will be seen, therefore, that the forward sheet 42 constitutes a flexible connection between the forward and intermediate portions 11-12 of the frame; and that the intermediate sheet 43 constitutes a flexible connection between the intermediate and rear portions 12-13. The ski slide will therefore conform to substantial irregularities of the ground, table or other supporting surface, longitudinally of the slide, the curvature of the runway being in part determined by the extent of such irregularities.

By providing the rearward pairs 20-21 of uprights of equal height, the rearward end portion 48 of the sheet 43 forms a substantially horizontal take-off platform for the ski jumper C.

Referring now to the ski slide B shown in Figure 2, and providing a continuous runway, the same is of a construction identical with the ski slide A just described, except that the pair 16 of companion uprights plus the upper and lower cross pieces 33 and 28 normally associated with these uprights are omitted. The pair 15 of companion uprights plus the upper and lower cross pieces 33 and 28 normally associated with the latter pair of uprights is then substituted for the omitted members, the sheet 42 at its 15 rearward end 49 being overlapped by the forward end 50 of the intermediate sheet 43.

The ski jumper C may be of any suitable construction but preferably includes a human figure 41 and a pair of skis 52 detachably secured to the feet of the figure, such as shown and claimed in my application for U. S. patent, filed September 21, 1938, Serial Number 231,081, which is now U. S. Patent 2,183,144 issued December 12, 1939.

From an inspection of Figure 7 of the drawings in the present application, it will be seen that the various parts of the ski slide and ski jumper may be compactly disposed for shipment and storage in a relatively small flat rectangular container D of a width equal to that of the sheets 42-43-44 and of a length equal to the height of the pairs 20-21 of companion uprights, the required height of the container being no greater than the transverse dimension of the uprights.

In the use of the ski slide and ski jumper as a game, the object is to cause the ski jumper to descend the runway without turning around or falling over. A little wax may be sprinkled on the slide to make it slippery. Then the jumper is placed at the top of the slide and given a start down the incline. If the jumper goes straight down the slide, the player scores 25 points; if backwards, 10 points; whereas if the jumper falls over, the player receives nothing.

It will be seen that the game, to be successfully played, requires practice as well as the exercise of skill and care on the part of the player.

Various changes may be made in the form of the invention herein shown and described, without departing from the spirit of the invention or the scope of the following claim.

I claim:

In a ski slide, an elongate frame comprising a plurality of independent structures disposed in spaced end to end relation and each including a plurality of spaced cross pieces lying in an arcuate path of travel, an elongate runway comprising resiliently flexible sheet means extending over said cross pieces and between adjacent structures of said frame, and means securing said sheet means to the respective cross pieces of said adjacent structures, whereby to flex said sheet means into alignment with said arcuate path of travel.

CHARLES D. McINTYRE.
